UNITED STATES PATENT OFFICE.

THEODORE F. OECHSLE, OF PHILADELPHIA, PENNSYLVANIA, ASSIGNOR TO DAVID LUPTON'S SONS COMPANY, OF PHILADELPHIA, PENNSYLVANIA, A CORPORATION OF PENNSYLVANIA.

PIPE-BENDING MACHINE.

Application filed November 9, 1921. Serial No. 514,093.

To all whom it may concern:

Be it known that I, THEODORE F. OECHSLE, a citizen of the United States, residing in Philadelphia, in the county of Philadelphia and State of Pennsylvania, have invented 5 certain new and useful Improvements in Pipe-Bending Machines, whereof the following is a specification, reference being had to the accompanying drawings.

10 My invention relates to pipe bending machines and more especially to apparatus for bending stove pipe or spout elbows from thin sheet metal tubes.

Amongst the objects of my invention are 15 to secure in such machines greater simplicity both as to construction and operation so that pipes of the class specified may be bent with absolute uniformity and precision and more expeditiously than possible with 20 devices heretofore designed for a similar purpose; to render the operation of the machines absolutely automatic; and to enable the crimps, necessary in effecting the bending, to be formed to the exclusion of 25 any possibility whatever of fracturing the metal of the pipes.

Other objects and attendant advantages 30 of my invention will become readily obvious from the detailed description which follows:

35 In the drawings, Figure I is a plan view of a pipe bending machine conveniently embodying my invention.

Fig. II is a side elevation of the same.

Fig. III is an elevation of the right hand 35 end of the machine considered with relation to the positioning of Figs. I and II.

Fig. IV is a longitudinal sectional view through the structure.

Fig. V is a cross section viewed in the 40 direction of the arrows V—V in Figs. I, II and IV.

Fig. VI is an illustration of a portion of the cam for actuating the reciprocating mandrel showing, in detail, a means whereby 45 the throw of the cam may be varied.

Fig. VII is a detail section viewed in the direction of the arrows VII—VII in Fig. VI.

Fig. VIII is a perspective view of the 50 aforesaid adjusting means.

Fig. IX is a detail cross sectional view along the lines IX—IX in Figs. I, II and IV.

Figs. X, XI, XII and XIII are detail

55 sectional views of the mechanism whereby the pipe is indented and crimped in the course of being bent into the form of an elbow,—Figs. XI and XIII being axial sections showing two different positions of this mechanism.

60 Fig. XIV is a detail plan section along the lines XIV—XIV of Figs. II and IV.

Figs. XV and XVI are perspective views of certain elements associated with the cross head whereby the pipe is moved relative to 65 the die mechanism.

Fig. XVII is a sectional view along the lines XVII—XVII in Figs. I and IV.

Fig. XVIII is a detail cross sectional view along the lines XVIII—XVIII in Figs. I 70 and II.

Fig. XIX is an illustration showing the type of elbow produced upon the pipe bending machines of my invention.

Fig. XX is a diagrammatical sectional 75 view along the line XX—XX of Fig. I, showing the details of a clutch mechanism whereby the operations of the machine are controlled.

Fig. XXI is a cross section through the 80 clutch proper along the lines XXI—XXI in Fig. XX.

Fig. XXII is a cross sectional view along the line XXII—XXII of Fig. XXI showing the clutch elements in inactive position; 85 and

Fig. XXIII is a view similar to XXII showing the clutch elements in active position.

90 In the embodiment which I have chosen for the purpose of illustration herein, the mandrel indicated at 1 is supported for reciprocation mainly by a bearing 2 which is mounted to the center of the top of a table 3 sustained at an appropriate height from the floor by means of standards or pedestals 4—4. The left hand end of the mandrel 1 is squared as represented at 5 and guided within a correspondingly shaped opening in the plate 6 of a bracket 7 which is secured 95 to a transversely extending, fixed axle shaft 8. Said shaft is clamped in bearings 9—9 bolted to the top of table 3 at the rear end of the machine. By the provisions just described the mandrel 1 is positively held 100 against rotation in the course of its reciprocations.

The mandrel derives its motion from a

rotary cam 10 on a shaft 11 journalled in appropriate bearings 12 and 13 which depend from the under side of the top of the table 3. The cam 10, as best shown in Figs. 5 I, IV and XVII, has replaceable riser segments 15-15 attached to opposite sides of a central peripheral flange 16. The segments 15-15, during rotation of the cam, alternately engage with rollers 17-17 of 10 the mandrel, thus causing the latter to be shifted back and forth within its bearings.

Guided by the reduced outer end 14 of the mandrel with capacity for independent axial shifting, is a cross head 18 which is 15 sustained upon a suitable machined slideway on the top of the table. Said cross head has an integral axial extension or neck 19 for attachment and support of an abutment plate 20. Said plate has a circular groove 21 adapted to receive the end of the pipe P which is to be bent into the form of an elbow. In practice I have found, in mounting the pipe about the mandrel, that insertion of its end within the groove 21 of the 20 plate 20 is greatly facilitated when the latter is accorded a certain amount of independent or free motion. To this end, the central opening of the plate 20 is made somewhat larger in diameter than that of the neck 19 25 of the cross head. The plate 20 is retained against displacement by aid of screw studs 22-22 which engage in vertical slots at the sides of the neck 19 as shown to best advantage in Figs. XIV and XVIII. The latitude thus afforded the abutment plate 20 also allows the pipe P to yield to a limited extent in the course of the bending operation. The pipe is moved forward step by 30 step under propulsion of the cross head 18 35 toward a die mechanism 23 which forms a succession of crimps in a manner which will be later explained. The cross head 18 is subject to the pull of a weight 24 appended to a chain 25 which is attached to a rod 26 40 extending rearwardly from said cross head. The rod 26 is guided in an upstanding apertured lug 27 on the cap piece of the bearing 2, and the chain 25 is in turn guided about a sheave 28 mounted for free rotation on a 45 fixed bracket 29.

The progressive forward movement of the cross head is brought about by means, and in a manner which may be briefly described as follows:

55 The rear end of the cross head 18 has a vertical central slot for accommodation and guidance of a gravity dog 30 (detailed in Fig. XVI of the drawings) adapted for co-operation with notches 31 on the top of the 60 reduced end 14 of the mandrel 1. The cross head furthermore carries a second gravity dog in the form of a yoke 32 which straddles the mandrel and whose vertical extremities 32'-32' are designed for co-ordination with 65 notches 33 of a toothed rack 34 fixed to the

top of the table 3 directly beneath the mandrel, see Fig. IV. Assuming the parts to be in the position shown in said figure and that the mandrel is being retracted, it will be apparent that in the course of this action, the dog 32, by reason of its engagement with the rack 34, holds the cross head stationary while the dog 30 will yield to being raised by the incline of the first notch 31 in the mandrel. When the latter is fully retracted the dog 30 will drop into the next succeeding notch 31 since the motion induced in the mandrel by the cam 10 in practice is substantially the same as the spacing of the notches. In the shifting of the mandrel in 70 the opposite direction, the cross head will be moved forward until the extremities of the dog 32 drop into the next adjacent notch 33 of the toothed rack 34. Thus it will be seen that said dogs are independently and 75 alternately operative and, moreover, that one acts as a check upon the other. In this way the pipe P is progressed forwardly, step by step, until the last notch 31 in the mandrel has functioned when the cross head is released to slide back upon the mandrel under pull of the weight 24 to its initial or starting position in a manner hereinafter set forth in greater detail. The dogs 30 and 32 are connected by means of a bolt 35 but this connection does not interfere with their normal independent action as aforesaid.

Referring now to the die mechanism 23, shown in Figs. III, V, X, XI, XII and XIII, it will be observed that the matrix 100 element is in the form of a head 40 secured to the outer end of the mandrel 1. Said head 40 comprises two disks 41 and 42 which are so configured as to afford between them, a crevice or forming groove 43 which, as best 105 seen from Figs. XII and XIII, extends about the greater portion of the periphery of the head. It is widest at the top and tapers gradually and symmetrically downward along the sides of the head to terminal points very close to the bottom of the latter. The disks 41 and 42 of the die head are held 110 in alignment by a dowel pin 44 and rigidly secured to the mandrel 1 by means of an axial bolt 45. Cooperative with the die head 115 40 are the opposing male die elements 46-46 which are exact complementary counterparts of one another and are bolted to the back of plates 47-47. Said plates 47-47 are carried by slides 48-48 mounted in a horizontal transverse guide-way formed jointly by uprights or standards 49-49 at the forward corners of the table 3,—a bridging piece 50 which spans the standards,—and a bottom strip 51 secured to the top of said 120 table between the standards. The parts 50 and 51 are grooved longitudinally for the 125 retention of tongues projecting from the tops and bottoms of the slides 48-48. Said slides are reciprocated in the transverse 130

guide-way through the instrumentality of a rotary cam 52 mounted upon the shaft 11 directly to the rear of the bearing 13 previously referred to. Said cam 52 has an appropriate endless cam groove, which, through a roller 53 serves to actuate an oscillating lever 54, the latter being centrally pivoted at 55 to the table 3. The ends of the lever 54 are coupled by means of links 56-56 with arms 57-57 mounted on the protruding ends of the shafts 58-58 which have bearing in the uprights 49-49. Secured to the shafts 58-58 within the hollows of the said uprights 49-49 are arms 59-59 which, in turn, are coupled, through toggle links 60-60, with the slides 48-48. Thus for each rotation of the cam 61, it will be seen that the slides 48-48 are advanced and retracted with respect to the mandrel 1.

Referring again to the plates 47-47, it will be observed more particularly from Fig. III, that they are adapted for independent vertical reciprocation relative to the slides 48-48 and are guided, and at the same time held to the slides, by means of bolts 61 which extend through slots 62. Reciprocatory motion is imparted to the plates by a rotary cam 65 secured to the shaft 11 with the cam 52 but to the outer side of the bearing 13. Cam 65 serves to actuate through a roller 66, an element 67 having, at its upper end, attached extensions with inwardly turned projections or tongues 68-68 which engage within horizontal grooves 69-69 in the front faces of the plates 47-47. This construction will obviously permit horizontal shifting of the slides 48-48 as previously explained. The die elements 46-46 have comparatively sharp semi-circular edges 70 which force the metal of the pipe P into the crevice or forming groove 43 of the matrix or head 40 to form an indentation in the manner best shown in Figs. X to XII inclusive. The cams 52 and 65 are so placed on the shaft 11 that indentation of the pipe is effected in two distinct stages. The cam 52 is the first to become operative and causes the die elements 46-46 to be shifted inwardly until they meet at the top as shown in Fig. X, and their arcuate sharp edges 70-70 bite into the sides of the pipe whereupon the cam 65 functions to withdraw the die elements downwardly to complete the indentation. By such stage-wise action in forming the indentations, the possibility of fracturing the metal of the pipe is absolutely prevented.

The cam 65 may be adjusted to vary the vertical movement of the male die elements 46-46 by aid of a plug 71, Figs. VI, VII and VIII. Said plug 71 has at its inner end a number of radial projections or ridges 72 and fits within a correspondingly shaped aperture 73 extending through the cam 65. The ridges 72 are of different lengths

radially and they may be used selectively to modify the groove of the cam at its innermost or draw point as clearly shown in Fig. VI. The rear end 74 of the plug 71 is cylindrical and the aperture 73 in the cam 70 is appropriately counterbored for its reception. The plug is held in place by means of a screw 75 which draws the same against a removable threaded plug 76 provided as a closure for the opening of the cam. 75

Immediately after the pipe has been indented as above noted, the male die elements 46-46 are withdrawn to their inactive positions and the die head 40 moved rearward with respect to the pipe as the mandrel is retracted. As a consequence of this movement of the head, the indentation of the pipe P is first closed and then folded under or crimped with the result that the protruding front end of the pipe is given an angular tilt or bend as clearly shown in Fig. XIII. The formation of the crimp is made possible through the assistance of an apertured plate 80 through which the head 40 moves and which is located directly to the rear of the path of movement of the die elements 46-46 and secured to a fixed supporting member 81. The opening 82 of the plate 80 is, in general, just large enough to accommodate the pipe P to steady the same and prevent spreading thereof during crimping. At its forward end said opening has a tapered internal circumferential recess 83 wherein the displaced metal of the pipe indentation is accommodated as it is folded over. The continued operation of the die mechanism in timed relation with the shifting of the pipe P under propulsion of the cross head 18 in the manner explained, results in the formation of a series of crimps C which, according to their number, obviously determine the angle of the bend of the finished elbow as will be apparent from Fig. XIX of the drawings. The number of crimps interposed in the pipe may be predetermined as will be presently disclosed. 100

In order to prevent displacement of the pipe P from the groove of the abutment plate 20 during the forward movement of the cross head 18 and also to assist in preventing spreading during bending, I have provided a supplemental implement in the form of a grooved disk 85, Fig. IV, adapted to be applied about the outer end of said pipe. Said implement has one or more set screws 86 whereby the pipe end is secured in its groove, and also a handle 87 adapted to be grasped by the operative of the machine for application of sufficient pressure, manually, to maintain the pipe seated in the groove of the buttress plate as aforesaid. 115

The machine is actuated by means of a continuously moving pulley 90 mounted for free rotation upon the fixed axle shaft 8 125

to one side of the machine. The pulley 90 has a rather heavy rim so as to be operative after the manner of a fly wheel in stabilizing the action of the various movable parts of the machine and may be coordinated with any suitable source of power, not shown. To the inner side of the pulley is fixed a gear wheel 91 which drives a gear 92 mounted upon a counter shaft 93. Said counter shaft 93 is journaled for rotation in bearings 94 of the table 3 and has secured to it a bevel gear 95 which, through an intermeshing bevel gear 96 serves to drive the shaft 11.

For the purpose of connecting and disconnecting the gear 92 from the shaft 93, I have provided a clutch mechanism which is shown in detail in Figs. XX to XXIII inclusive. This mechanism is housed within a casing 97 formed integrally at one side of the gear 92 and includes a collar 98 which is keyed to the shaft 93. Said collar 98 has pivoted to it a dog 99 which is adapted to cooperate with internal teeth 100 of the casing 97. Said casing is closed by a cover plate 101 which is free to rotate on shaft 93 and from which projects inwardly, lugs 102 and 103. The former 102 of these lugs is bored to receive and guide a spring pressed plunger 105 which engages one end of the dog 99 and tends to maintain the same out of engagement with the teeth 100 in opposition to a spring 106 carried within a suitable socket in the collar 98, said latter spring 106 tending to normally maintain the dog 99 in active position or in engagement with the teeth 100, see Fig. XXIII. An axial boss 110 of the cover plate 101 has an integral outstanding cam lug 111 adapted to be engaged by a hook in the end of a control lever 112 which is pivoted at 113 to the side of the table 3. A spring 114 serves to maintain the hook of the lever 112 in engagement with the stop lug 111, to hold the clutch disconnected. When the machine is to be started, the handle of the lever 112 is depressed which results in release of the casing cover 101 and is locked by means of a hook 116 pivoted at 117 to the top of the table 3, said hook 116 engaging with the notched arm 118 secured on the fulcrum shaft 113 with the lever 112. A stop 115, by cooperation with a fixed stud 119 projecting from the frame 3, prevents excessive motion of the lever 112. The hook 116 has an upstanding projection 120 which lies within the path of an adjustable screw 121 in an arm 122 projecting laterally from the cross head 18 as clearly shown in Figs. I and XIV. Thus it will be seen that as the cross head 18 reaches the forward limit of its travel the screw 121 will engage the upstanding end 120 of the hook 116 to release the latter from engagement with the element 118.

Thereupon the spring 114 becomes effective in shifting the control lever 112 so that its hook moves into the path of the stop lug 111, thereby causing withdrawal of the pawl 99 from the teeth 100 and disconnection of the clutch mechanism.

The cam 10 is prevented from overthrowing upon disconnection of the clutch mechanism by means of a stop dog 125 adapted to engage within a notch 126 in the periphery of said cam as clearly shown in Fig. XVII. Said stop dog 125 it will be noted is spring pressed and hence capable of yielding during initiation of the movements of the said cam 10.

After the cross head 18 has been moved forward to the fullest extent, it is released automatically to withdraw to the original or starting position under the pull of the weight 24 in preparation for a succeeding bending operation. This is accomplished by a trip mechanism 130 carried by the cross head. Said mechanism includes a shaft 131 mounted for free oscillation in the cross head 18 and having, at one end, an arm 132 which is subject to the pull of a spring 133 operative in maintaining said arm in angular position at opposite sides of the perpendicular through the center of the shaft 131. To the other end of the shaft 131 is secured an element 135 having a finger 136 which together with a similar finger 137 forming a part of the arm 132 previously referred to, is adapted to engage beneath outstanding projections of the yoke dog 32 (see Figs. II and IX) to lift the same together with the dog 30 (the latter, it will be remembered being connected by means of the bolt 35) to release said dogs simultaneously from engagement with the notches 31, 33, in the mandrel 1 and the rack 34 respectively. The last or outermost tooth of the mandrel 1, is made purposely smaller than the others and serves, after the last crimp has been made in the pipe, to move the cross head 18 forward an additional step—just sufficient to bring about engagement of the element 135 with an extension 138 projecting from one of the arms 56 of the die mechanism. In encountering the extension 138 the element 135 will be rotated clockwise and thus swing the arm 132 to a position on the opposite side of the center of shaft 131 in which position it will remain until again engaged upon full retraction of the cross head as will be subsequently disclosed. In its rearward movement, after being freed as just explained, the cross head 18 encounters a stop 140 (Figs. I, II and XIV) which is removably supported upon a ledge at the side of the bearing 2 and held from displacement by a guard plate 141. The rear end of the stop 140 abuts against a lug 142 projecting laterally from the side of the

mandrel 1. The limit to which the cross head 18 is retracted may be varied simply by removing the stop 140 and replacing the same by other stops of the same character but of different lengths. By this arrangement, various numbers of the teeth 31 of the mandrel 1 may be employed in obtaining corresponding variations in the number of crimps produced in the pipe and in the angle of the resulting elbow.

In the course of the retraction of the cross head 18, the element 135 of the trip mechanism 130 is engaged by the end of a tappet rod 145 projecting forwardly from the bearing 2 so that the dogs 30 and 32 are freed to resume active positions. Said rod 145 is shouldered as at 146 and may be set in different adjusted positions (in accordance with the adjustments of the stop 140 for the cross head) simply by transposing one or more of the collars 147 from the back end of the rod to a position intermediate its shoulder 146 and the front face of the bearing 2.

It is thought that the successive steps involved in bending of a pipe into the form of an elbow according to my invention are readily understandable from the foregoing and a separate detailed description of the operation of the machine has therefore been omitted to avoid unnecessary repetition.

Having thus described my invention, I claim:

1. A pipe bending machine comprising a die mechanism for crimping the pipe to be bent, a reciprocating mandrel provided with notches about which the pipe is placed, a cross head for progressing the pipe step by step through the die mechanism, a gravity dog carried by said cross head adapted to cooperate with the notches in the mandrel in locking the head to the mandrel during the forward movement of the latter, a fixed rack, and a second gravity dog cooperative with said fixed rack in holding the head in check during retractions of the mandrel.

2. A pipe bending machine comprising a die mechanism for crimping the pipe to be bent; a reciprocating mandrel about which the pipe is placed; a cross head for progressing the pipe step by step through the die mechanism; a dog carried by said cross head adapted to cooperate with notches in the mandrel in locking the head to the mandrel during the forward movements of the latter; a fixed rack a second dog cooperative with said fixed rack in holding the head in check during retractions of the mandrel; and means for simultaneously withdrawing said dogs after a predetermined number of crimps have been formed in the pipe to permit the cross head to resume a normal or starting position.

3. A pipe bending machine comprising a die mechanism for crimping the pipe to be

bent; a reciprocating mandrel about which the pipe is placed; a cross head for progressing the pipe step by step through the die mechanism; a gravity dog carried by the cross head adapted to engage with notches in the top of the mandrel in locking the head to the mandrel during forward movements of the latter; a fixed rack; a second gravity dog in the form of a yoke spanning the first mentioned gravity dog and the mandrel and having the ends of its vertical extremities cooperative with said fixed rack in holding the head in check during retractions of the mandrel; and means for simultaneously lifting the dogs to inactivity after a predetermined number of crimps have been formed in the pipe to permit the cross head to resume a normal or starting position.

4. A pipe bending machine comprising a die mechanism for crimping the pipe to be bent; a reciprocating mandrel about which the pipe is placed; a cross head for progressing the pipe step by step with respect to said die mechanism; a gravity dog carried by said cross head adapted to engage with notches in the top of the mandrel in locking the head to the mandrel during the forward movements of the latter; a fixed rack; a second gravity dog cooperative with said fixed rack in holding the cross head in check during retractions of the mandrel; a trip mechanism carried by the cross head, said mechanism including a rock shaft; yielding means for maintaining the rock shaft in either of its extreme positions; fingers carried by said rock shaft adapted to engage the dogs; means for actuating the trip mechanism to move the dogs to inactivity after a predetermined number of crimps have been formed in the pipe, to permit the cross head to retract to a normal or starting position; and means for again actuating the trip mechanism to restore the dogs to activity when the cross head has resumed its normal or starting position.

5. A pipe bending machine comprising a die mechanism for crimping the pipe to be bent; a reciprocating mandrel about which the pipe is placed; a cross head for progressing the pipe step by step through the die mechanism; a gravity dog carried by said cross head adapted to engage with notches in the mandrel in locking the cross head to the mandrel during the forward movements of the latter; a fixed rack; a second gravity dog cooperative with said fixed rack in holding the cross head in check during the retractions of the mandrel; means for tripping said dogs simultaneously after the completion of the bending operation to permit the cross head to retract to a normal or starting position; and an adjustable stop whereby the limit of retraction of said cross head may be varied with re-

spect to the notches in the mandrel in pre-determining the number of crimps made at each actuation of the machine.

6. The combination in a pipe bending machine of a die mechanism, a matrix in the form of a head and notched mandrel over which the pipe to be bent is mounted, said head comprising appropriately configured disks affording a forming groove extending about its periphery, means retaining said disks in rigid alignment, horizontally movable cooperative male die elements adapted to force the metal of the pipe into the forming groove of said head, and a gravity dog for shifting the notched mandrel and head bodily to close the indentation in the pipe and to fold over the displaced metal into the form of a crimp.

7. In a pipe bending machine comprising

die mechanism for crimping the pipe to be bent, a head for removing the pipe with respect to the die mechanism, and said head being appropriately recessed to receive and sustain one end of the pipe, the combination of a grooved disk for clamping connection to the opposite end of the pipe, said disk being provided with a handle whereby an operative, by pressure thereon, may maintain the pipe engaged within the aforesaid cross head.

In testimony whereof, I have hereunto signed my name at Philadelphia, Pennsylvania, this 1st day of November, 1921.

THEODORE F. OECHSLE.
